CLAIM

The ornamental design for a fluid distribution system, as shown and described.

DESCRIPTION

FIG. 1 is a front view of a fluid distribution system; FIG. 2 is a back view of the fluid distribution system; FIG. 3 is a right view of the fluid distribution system; FIG. 4 is a left view of the fluid distribution system; FIG. 5 is top view of the fluid distribution system; FIG. 6 is bottom view of the fluid distribution system; and, FIG. 7 is a perspective view of the fluid distribution system. In the drawings, the equal-length broken lines depict portions of the fluid distribution system that form no part of the claimed design.

1 Claim, 4 Drawing Sheets(56)
